UNITED STATES PATENT OFFICE.

WILLIAM J. DRUCKER, OF NEW YORK, N. Y., ASSIGNOR TO NATIONAL MAYONNAISE MACHINE COMPANY, INC., OF BROOKLYN, NEW YORK, A CORPORATION OF NEW YORK.

EMULSIFIER.

Application filed March 24, 1920. Serial No. 388,381.

To all whom it may concern:

Be it known that I, WILLIAM J. DRUCKER, a citizen of the United States, and a resident of the city of New York, Woodhaven, 5 borough of Queens, in the county of Queens and State of New York, have invented a new and Improved Emulsifier, of which the following is a full, clear, and exact description.

10 This invention relates to mixing devices or emulsifiers and while it is designed particularly for the making of mayonnaise, it may be used for the making of any kind of emulsions or other mixtures that require 15 agitation for a long period of time.

Among the objects of the invention is to provide an emulsifier of a simple, inexpensive construction which may easily be kept sanitary.

20 Figure 1 is a side elevation with the parts in vertical section.

Fig. 2 is a horizontal section on the broken line 2—2 of Fig. 1.

Fig. 3 is a vertical sectional detail on the 25 line 3—3 of Fig. 1.

Fig. 4 is a horizontal section on the line 4—4 of Fig. 1.

Fig. 5 is a horizontal section on the line 5—5 of Fig. 6.

30 Fig. 6 is a vertical section on the line 6—6 of Fig. 5.

Fig. 7 is a perspective view of the receptacle bottom.

In the drawings the base 7 carries a motor 35 8 and any suitable gearing, not shown, which couples the motor to a platform 9 supported by the base for rotary movement thereon. The platform is provided with an annular groove 10 near its margin, leaving 40 an annular flange at the marginal edge of said platform. A series of lugs extend transversely across the annular groove 10 from the marginal edge flange to the surface on the central portion of the platform.

45 These lugs are spaced apart at intervals, preferably 90 degrees.

The receptacle 12 and its bottom 13 is raised so that the wall of the receptacle extends below the bottom to enter the groove 50 10, the extending portion of the bottom having notches 14 to receive the lugs 11 whereby the receptacle is fixed to the platform to rotate therewith and is encompassed at the extending portion of the wall thereof by

the annular marginal flange of the platform. By spacing the lugs equally the operator is not required to give any special attention to the positioning of the receptacle when placing it in the groove. The bottom 13 has a central socket 15 to receive 60 a centering stud 16 on the platform whereby the receptacle is prevented from movement laterally in any direction.

The base 7 has lugs 17 from which posts 18 extend upward to support a frame 19 which holds the container 20 from which oil or the like may be discharged in graduated quantities into the receptacle. The support 19 has at one side of its center a depending lug 21 which is preferably integral therewith and to which a stationary stirrer 22 may be secured by a clamping screw 23. The top of the stirrer is provided with a slot 24 into which extends a plate 25. The slotted portion of the stirrer is provided with a plurality of transverse bolts 26 which pass through holes 27 formed in the lower end of the plate which are considerably larger than the bolts. The plate and lug 21 are provided with mating pins 28 and holes 29 whereby the plate is locked rigidly to the lug 21 when the screw 23 is tightened. With the bolts 26 sufficiently loose the stirrer may be adjusted with respect to the plate 25 to accommodate the stirrer to any irregularities that may occur in various makes of receptacles. After the proper adjustment has been made the bolts 26 are tightened making a permanent rigid connection between the stirrer and said plate. For cleansing purposes it is therefore necessary only to separate the stirrer from the other parts of the machine, and for cleansing purposes the bolts 26 need not be loosened. The screw 23 has 85 a long shank for convenience in manipulation beyond the frame 19. The bottom of the stirrer is arched upward at 30 to permit sticky materials from lodging between the stirrer and the bottom 13 of the receptacle. By providing for the rotation of the receptacle while the stirrer remains stationary I am able to emulsify much more rapidly and thoroughly than if the stirrer were caused to rotate in a stationary receptacle.

By reason of the portion of the wall of the receptacle extending below or beyond

the bottom of the receptacle and into the annular groove 10, the said extending portion of such wall is encompassed by the annular marginal flange formed on the platform, and hence the receptacle is braced and supported against the effects of centrifugal power developed by the axial rotation of the receptacle and its contents during the emulsifying operation.

10 From the foregoing description it will also be seen that the receptacle may be quickly placed in position with the lugs 11 entering and engaging in the slots 14, or detached and removed from the platform 15 and without any special care required and without the danger of the receptacle becoming wedged upon the lugs through swelling or expansion of the receptacle resulting from the use of liquids in the machine.

20 I claim:

1. In an emulsifier, a base, a rotatable platform carried by the base, said platform having an annular groove in the supporting

surface thereof near its margin leaving an 25 annular flange at the marginal edge of said platform, provided with lugs extending transversely across said groove from said marginal flange, a receptacle carried by the platform, said receptacle having side walls 30 extending into said annular groove and formed with notches to receive said lugs, and means for rotating said platform whereby through the engagements of said lugs and receptacle the latter will be ro- 35 tated.

2. In an emulsifier, the combination of a rotatable receptacle, a frame above the receptacle and having a depending stationary lug, a stirrer, a plate, means to connect 40 the plate to the stirrer comprising clamping means passing through registering holes formed in the plate and stirrer, said holes being of different sizes to provide for lateral adjustment of one part with respect to the 45 other and means to connect the plate to said depending lug.

WILLIAM J. DRUCKER.
